UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

PAPER CONTAINER.

Application filed August 25, 1922. Serial No. 584,168.

To all whom it may concern:

Be it known that I, WILBUR L. WRIGHT, a citizen of the United States of America, and resident of Fulton, county of Oswego, State of New York, have invented certain new and useful Improvements in Paper Containers, of which the following is a specification.

This invention relates to certain improvements in paper containers, and the objects 10 and nature of the invention will be readily understood by those skilled in the art in the light of the following explanations of the accompanying drawings that illustrate what I now believe to be the preferred mechanical 15 expressions or embodiments of my invention from among other forms, constructions and arrangements within the spirit and scope thereof.

An object of the invention is to provide 20 certain improvements in the end closures, particularly the so-called double bottoms of paper cans, with the ends in view of attaining maximum economy in production and of reducing to the minimum possibility of 25 liquid content leakage and derangement of the closure parts.

With these and other objects in view my 30 invention consists in certain novel features in construction, and in combinations and arrangements, as more fully and particularly set forth and specified hereinafter.

Referring to the accompanying drawings, forming a part hereof.

Fig. 1 is a sectional elevation of a paper 35 can having a double end closure constructed in accordance with my invention.

Fig. 2 is a detail vertical section showing 40 the end closure formation of Fig. 1 on an enlarged scale.

Fig. 3 is a sectional elevation of a wound 45 paper tube or barrel having the relatively thin flanged disk and the relatively thick flat disk, inserted in the upper end of the tube, preparatory to the formation of the completed end closure.

Figs. 4 and 5, are detail sections, on an 50 enlarged scale, showing modified formations.

The barrel or tube 1, is, in the particular 55 example illustrated, cylindrical and formed of spirally wound sheet paper material although I do not wish to so limit my invention. The barrels of the cylindrical paper cans of commerce are usually formed on so-called, paper tube winding machines. These tubes or barrels 1, as thus formed, are

usually multi-ply, and comparatively stiff and strong, and are preferably treated to render the same approximately leak proof.

These paper cans are usually provided with flanged slip covers struck up from sheet paper material, or composed of a length of spirally wound paper tube or barrel having an end closure locked therein and thereto by crimping, and if so desired, my hereinafter described invention can constitute the end closure of a barrel to form a slip cover, as well as the double bottom of a can.

The end closure consists of an imperforate inner flanged paper-material disk 2, 70 set down in the barrel 1, an imperforate outer paper-material disk 3 driven into the annular flange 2^a and held to the disk 2, and locking crimp 4 by which said disks become, in effect, permanent parts of the 75 barrel, and which provide the can with an annular flange or base depending from the can bottom, so that the can bottom is inset.

The crimp 4 is composed of the disk flange 2^a and the projecting end 1^a of the 80 barrel, and is formed by doubling or forcing said end and flange inwardly and upwardly (by referring to Figs. 1, 2, 4, 5) by a spinning, rolling, swaging or crimping action to mash or compress the paper walls 85 together and tightly seat the inner end 4^a of the crimp against the edge portion of the outer face of the outer disk 3 and lock the outer disk in the can as a permanent part of the bottom thereof co-operating with the flanged disk and the barrel 1, to reduce to the minimum possibility of leakage of the liquid contents of the can between the inner surface of the can barrel and the flanged disk 2. The flanged disk 2 is struck up from 90 relatively thin sheet paper material with an exterior diameter to permit the disk to be pushed longitudinally into the open upwardly projecting end of the paper barrel 1, in the process of assembling the can parts 95 100 in a suitable machine.

The outer disk 3 is cut from relatively thick sheet paper material, so as to be of approximately "over size" external diameter with respect to the internal diameter 105 of the flange 2^a of the flanged disk. In other words, the diameter of the outer disk is preferably, but slightly greater than the internal diameter of the flange 2^a into which said outer disk is inserted in the proc- 110

ess of assembling the cam parts. Fig. 3 is intended to show the preferably slightly over large diameter of the outer disk 3 by indicating that the outer disk can be inserted only partially into the flanged disk unless forcing pressure is applied to slightly expand the flange in driving the outer disk 3 onto and into parallelism with the inner disk 2. When the outer disk is thus driven down onto the inner disk, the flange 2^a is expanded into tight intimate approximately merging contact or engagement with the inner surface of the barrel 1.

The outer disk 3 can be thus forced down into the flange 2^a and against the disk 2 by the descending rotating spinning or crimping head of can bottoming and crimping machine, which forms the crimp 4 and compresses the two disks and the crimp 4 tightly together and against the top die plate of the mandrel. The peripheral edge portion of the disk 3 will remain approximately flat or horizontal as in Figs. 1 and 2, if the die plate and head of the machine are flat.

The disk edges 2^c, 3^b in the completed article can be flared or turned downwardly as in Fig. 4, by employing a die plate of the desired formation; or turned or flared upwardly, see 2^d, 3^c, Fig. 5, by employing a die plate of the necessary formation.

The problem is to produce a liquid tight can, i. e. to reduce to the minimum possibility of liquid leakage through the can bottom, and at the same time, such a construction as to (1) permit quantity production by appropriate machinery, (2) reduce to the minimum the quantity of paper stock or material in each can, and (3) permit the use of the maximum percentage of low grade or comparatively inexpensive paper material in each can.

This problem was solved by providing the outer disk 3 driven in and expanding the flanged disk with the bottom locking crimp compressed against such disk and maintaining the same in operative position upholding and supporting the disk 2 in such manner that disk 2 cannot sag and tend to open the seam or joint between flange 2^a and barrel 1, to liquid seepage, and so that the disk 2 faces the disk 3 against contact with the liquid contents of the can, and also against the loosening influence of the minus pressure within the can when a close fitting slip cover is quickly removed from the open end of the can. The outer disk 3 fits within the disk flange 2^a, at the base of said flange where it turns or bends down from the flat body of the disk and expands said flange at 2^b, Fig. 2, 2^c, Fig. 4, or 2^d, Fig. 5, until the circumferential edge of the disk 3, and the surfaces of the flange 2^a and barrel 1, are approximately swaged together or driven into

each other, to provide an annular liquid tight joint between the can barrel 1 and the flanged disk 2.

The pressure applied during the complete seating of the outer disk within the flanged disk and the formation and the locking of the crimp 4, draws the disks and barrel so tightly together as to almost amalgamate the engaging paper material surfaces around the circumference of disk 3 and almost cause exterior radial bulging of the can barrel annularly around the circumference of the disk 3. The drawings give an exaggerated idea of such a bulge for the purpose of illustrating the radial expanding force and pressure to which the barrel and flange 2^a are subjected by the disk 3 and the crimping operation. As a matter of fact, the completed can embodying my invention does not disclose an exterior bulge of the barrel and my invention is not limited to the formation of such a bulge, particularly as the preferred form of paper can bottoming machine provides an annular abutment around the portion of the barrel surrounding disk 3 that resists such barrel bulging and irons out such a bulge if it should be formed.

The purpose of the disk 3 is not to either contact or bulge the barrel, but to insure a tight joint between the inner disk flange and the barrel and to support the flanged disk to maintain such joint against leakage, and by reason of this disk and the peculiar relation between the disk and locking crimp, I am enabled to form the flanged disk of relatively thin as well as cheaper paper material than heretofore, particularly where formed with a proper surface or coating at its side that contacts the contents of the can. Any tendency of the disk flange to swell under the influence of the contents of the can, will tend to tighten the joint compressed between the periphery of disk 3 and the can body. The disk 3, is formed of stiff paper material, relatively thick with respect to the flanged disk, yet as disk 3 is covered from the can contents, by the flanged disk, I can employ cheaper paper material than is necessary where the flat or non-flanged disk of a double bottom, receives or contacts the can contents.

The advantage in my device, is gained by seating the outer disk within the flanged disk before or by the crimping operation so that the crimp is compressed longitudinally of the can against the outer disk. I also gain an advantage by so forming the up or longitudinally inturned portion of the crimp as to provide an annular crimp locking or bracing knee that flares upwardly and inwardly from the intermediate outward annular bulge 4^b to the crimp edge 4^a that abuts the under surface of disk 3. The annular outward bulge 4^b abuts the flange 2^a

above the doubled crushed lower end thereof embedded within the crimp, and as the upturned wall of the crimp is compressed upwardly against disk 3 with its upper edge 5 turned outwardly, said knee forms an effective lock against opening or release of the crimp.

The term paper material is employed herein in a generic sense to include fibrous sheet material suitable for the purpose, such as paper, paper stock, pulp board, so-called paste board, and the like.

It is evident that various changes, modifications, variations might be resorted to 15 without departing from the spirit and scope of my invention and hence I do not wish to limit myself to the exact disclosures hereof.

What I claim is:—

1. A paper material container having an 20 end closure embodying a relatively thin annularly flanged inner closure disk within the container barrel, and an outer flat disk of oversize with respect to the diameter of said annular flange and driven thereinto 25 against the flanged disk and maintaining radial expansive pressure against the base portion of said flange and driving the same into merging contact with the inner surface of the barrel to prevent liquid leakage 30 longitudinally of the flange and inner surface of the barrel, the disks being permanently secured in and to the barrel by a locked crimp embodying a doubled end portion of the barrel forming an annular knee bearing 35 inwardly against the outer surface of the rim portion of said oversize disk with the inner disk flange crushed within the doubled end portion of the barrel to lock the inner disk to the outer disk.

2. A paper material barrel having an internal paper material closure embodying a relatively thin inner disk having an annular out-turned flange within the barrel, and a relatively thick oversize outer disk facing the outer side of the flanged disk 45 and compressed within the flange of said disk and radially and annularly expanding said flange into liquid tight engagement with the inner surface of the barrel, the disks being locked to and within the barrel 50 by a locked crimp forced against the outer surface of the outer disk with the flange of the inner disk locked in and by said crimp and thereby holding the inner disk to and against inward movement from the outer 55 disk.

3. In the method of end closing a paper container barrel, those steps which consist in longitudinally inserting a relatively-thin paper-material annularly-flanged closure 60 disk into the barrel through one end thereof with the disk flange outturned and fitting the inner surface of the barrel: forcibly driving a relatively-thick oversize paper material disk into said annular flange within 65 the barrel to a position parallel with and against the outer surface of the flanged disk, and thereby radially and annularly expanding the base portion of said annular flange against the inner surface of the barrel; and 70 forming the barrel end and flange under swaging compressing force into a locked crimp against the outer surface of said oversize disk with the inner disk flange upset and locked within the barrel end. 75

Signed at Fulton, New York, this 23d day of August, 1922.

WILBUR L. WRIGHT.
